US0D1109926S

(12) **United States Design Patent** (10) **Patent No.:** **US D1,109,926 S**
(45) **Date of Patent:** **** Jan. 20, 2026**

(54) **HAIRDRESSING APPARATUS NOZZLE**

(71) Applicant: **BABYLISS FACO SRL**, Wandre (BE)

(72) Inventor: **Aubry Ernote**, Theux (BE)

(**) Term: **15 Years**

(21) Appl. No.: **35/521,460**

(22) Filed: **Jun. 10, 2024**

(80) **Hague Agreement Data**

Int. Filing Date: **Jun. 10, 2024**

Int. Reg. No.: **DM/237928**

Int. Reg. Date: **Jun. 10, 2024**

Int. Reg. Pub. Date: **Jun. 28, 2024**

(30) **Foreign Application Priority Data**

Dec. 13, 2023 (EM) 015044234-0006

Primary Examiner — Xavier Marti-Santos

(57) **CLAIM**

The ornamental design for a hairdressing apparatus nozzle as shown and described.

DESCRIPTION

1. Hairdressing apparatus nozzle

1.1: Perspective

1.2: Back

1.3: Left

1.4: Bottom

1.5: Front

1.6: Perspective

1.7: Top

1.8: Right

The characteristic elements of the design are featured in the shape of the hairdressing apparatus nozzle as represented.

1 Claim, 8 Drawing Sheets
